UNITED STATES PATENT OFFICE.

LEO KELLER, OF NEW YORK, N. Y., ASSIGNOR TO WESTERN ELECTRIC COMPANY, INCORPORATED, OF NEW YORK, N. Y., A CORPORATION OF NEW YORK.

TELEPHONE SYSTEM.

Application filed July 20, 1920. Serial No. 397,596.

To all whom it may concern:

Be it known that I, LEO KELLER, a citizen of the United States, residing at New York, in the county of New York, State 5 of New York, have invented certain new and useful Improvements in Telephone Systems, of which the following is a full, clear, concise, and exact description.

This invention relates to improvements in 10 telephone systems and has particular reference to a private branch exchange system employing machine switching.

In establishing connections within the 15 private branch exchange and outgoing calls to a central office, the invention contemplates the use of line finders and connectors, the latter switches being directly responsive to impulses for connections to subscribers within the exchange and also capable 20 of trunk hunting when establishing outgoing calls to central office or to the private branch exchange attendant. It has been customary, in systems embodying these general characteristics, when establishing incoming calls, to signal the private branch 25 exchange attendant over a central office trunk. The attendant then dials for the wanted subscriber over connections independent of said trunk and, upon the response of the subscriber, his line is connected, either automatically or manually, to the incoming trunk.

An object of the present invention is to 30 employ portions or extensions of incoming trunks and the same connecting circuits used in establishing calls within the private branch exchange in completing central office connections to a subscriber within said exchange.

In accordance with this object the private 35 branch exchange attendant is preferably provided with a key or other switch associated with an incoming trunk and which, when operated, will cause a line finder to seek and engage terminals to which an extension of said trunk is connected. The attendant may then operate connector switch 40 to establish connection with a subscriber by the transmission of impulses over said extension and through the line finder.

A preferred embodiment of the invention is illustrated in the accompanying drawings, wherein Figs. 1 and 2 with Fig. 1 at the left of Fig. 2, show diagrammatically 45 the circuit arrangement employed.

Fig. 3 is a diagrammatic view of the trunking arrangement of the line finder and connector switches used in connection with the invention.

Briefly, the invention contemplates the 50 use of rotary single movement switches which are capable of extending incoming calls from central office through an attendant's position at the private branch exchange to a subscriber therein, calls between subscribers or a subscriber and the attendant within the exchange, and outgoing calls from subscribers or the attendant to central office.

The inventive idea involved in the invention may be generally understood by 55 reference to Fig. 3 of the drawings. There is here shown a line finder A, the bank of which includes terminals to which a number of subscribers' lines and central office trunks may be extended. The terminals of the lines and trunks may be arranged in any desired manner. Connected to the brushes of the line finder is a connector B. Terminating in the bank of the connector 60 and utilizing certain of the terminals thereof are groups of central office trunks, subscribers' lines and attendants' trunks. Certain other of the terminals of the connector bank are allotted for group selection and 65 may be interspersed between terminals of the several groups.

On an incoming call from the central office, the call is routed through the attendant who, in a manner which will appear in the 70 course of the description, causes the line finder A to operate and engage the brush thereof with the terminal individual to an extension of the central office trunk taken for use. The attendant then dials the number 75 of the wanted subscriber. If said subscriber is in the group of lines having the digits 41 to 44, the impulses corresponding to the tens digit will operate the connector switch to engage the brush thereof with the 80 fourth terminal. The next or units impulses then causes the connector to select the desired line in the selected group. If the desired line is in the group marked lines 85 94-98, the nine impulses of the tens digit 90 steps the connector to the ninth terminal and the second series of impulses carries the switch over the tenth terminal and terminals of the attendant's trunks to the desired line. Should the wanted subscriber be in the last 95 100 105 110

group, it is necessary to transmit three series of impulses, the first two of nine each stepping the connector to the terminal marked 99 which is the eighteenth terminal in the bank and the last series engaging the brush of the connector with the terminal of the desired line. Subscribers within the exchange may establish connections in the same manner after the line finder has engaged the terminals of the calling line.

A subscriber desiring a central office connection transmits one impulse to cause the switch to take one step and then automatically hunt for an idle trunk in the group assigned for central office traffic. Should a subscriber wish a connection to the attendant, ten impulses are sent to engage the tenth terminal which is allotted for attendant's trunk selection. The switch again automatically hunts for an idle path leading to the attendant's position over the group of terminals AT.

It is believed that the invention will now be fully understood from the following detailed description of the establishment of the various connections.

Incoming call from central office.

When the central office operator inserts a plug of a cord circuit into jack 100, a well known circuit is closed to light the central office supervisory lamp associated with the cord taken for use and to energize cut-off relay 101 in the usual manner, thus disconnecting the line relay 102 from the trunk. A suitable cord circuit is shown in Patent No. 1,125,965 of January 26, 1915, to E. H. Clark. A circuit is also closed from battery in the cord circuit through the usual supervisory relay therein, the ring contacts of the plug and jack 100, the winding of supervisory relay 103, the right-hand normal contact of the relay 104, the winding of relay 105, the tip contacts of jack 100 and the plug engaged therein, to ground. Relay 105 is energized but is of such high resistance that the supervisory relay in the central office cord circuit is prevented from operating. The energization of relay 105 closes a circuit extending from grounded battery through the winding of slow to release relay 106 and the contact of relay 105 to ground. Relay 106 energizes and places a guarding potential on the sleeve conductor of the trunk in the connector multiple, to prevent seizure of said trunk when a call is initiated to the central office by a subscriber within the private branch exchange. The energization of relay 106 also establishes an obvious circuit for relay 107 which, upon energizing, lights the busy lamp 108. When the central office operator actuates her ringing key, supervisory relay 103 operates from the ring side of the trunk through the winding of said relay, the condenser 109

and the left-hand normal contact of relay 110 to the tip side of the trunk. Relay 103 energizes and remains in this condition during the actuation of the ringing key and upon operating establishes an obvious circuit for relay 104 which, upon energizing, opens at its right-hand normal contact the previously described circuit for relay 105 which then releases. The release of this relay opens the energizing circuit initially described for relay 106 but, this relay being slow to release, the energization of relays 103 and 104 establish other holding circuits for the same. The energization of relay 104 also includes the non-inductive resistance 190 associated with relay 103 in parallel with the inductive winding thereof. At its outer left hand alternate contact relay 104 also establishes a circuit for relay 111 extending from grounded battery through the winding of said relay the outer alternate contact of relay 104 and the normal right hand contact of slow to release relay 112 to ground. Relay 111 energizes and locks through its right-hand contact to ground at the normal contact of relay 112 and at its left-hand contact establishes the circuit for lighting the line lamp 113 which indicates to the attendant at the private branch exchange that a call on the particular trunk is awaiting attention. The attendant, with her receiver removed from its switchhook, then actuates the listening key 114 whereupon a circuit is established from grounded battery through the left-hand winding of line relay 115, the middle normal contact of relay 110, the middle normal contact of the central office cut-off key 116, the right-hand contact of the listening key 114, the attendant's substation set 117, the left-hand contact of the listening key, the upper normal contact of the central office cut-off key, the right-hand normal contact of relay 110 and the right-hand winding of relay 115 to ground. Relay 115 energizes and establishes a circuit for relay 112 extending from grounded battery through the winding of said relay and the right-hand contact of relay 115 to ground. Relay 112 energizes and opens the locking circuit for relay 111 which thereupon releases to extinguish the line lamp 113. The energization of relay 112 also establishes a circuit for relay 110 extending from grounded battery through the winding of said relay, the left-hand alternate contact of relay 112 and the inner right-hand alternate contact of relay 106 to ground, this relay being still energized due to the re-energization of relay 105 at the termination of the operation of the ringing key which energized relays 103 and 104. Relay 110 energizes in the circuit described therefor and at its right hand normal contacts opens the circuit for line relay 115 which thereupon releases, but the energiza-

tion of the relay 110 provides a holding circuit for relay 112 to ground through the left hand alternate contact of relay 110. The energization of relay 110 also connects 5 the trunk through to the attendant's telephone and at its left hand normal contact opens the bridge across the trunk which includes the condenser 109. The trunk having been extended through to the attendant's position, 10 the cord circuit supervisory relay at the central office and the supervisory relay 103 thereupon energize in the usual manner, the operation of the former relay extinguishing the supervisory lamp in the cord circuit. Relay 103, in operating again causes the energization of relay 104 which disconnects relay 105 from the line and provides a holding circuit for relay 106. Relay 104 again includes the non-inductive resistance 15 190 in the line circuit for talking purposes. A connection is now established from the calling subscriber through the central office to the attendant at the private branch exchange who may now communicate with 20 said subscriber to obtain the details of the connection desired.

Having ascertained the number of the wanted subscriber, the attendant operates the central office cutoff key 116 which at 25 its upper alternate contact establishes an obvious circuit for relay 118, and this relay in closing its left hand contacts connects the holding bridge 119 across the trunk to hold the connection while the attendant proceeds 30 to call the wanted subscriber. The operation of the key 116 opens the talking circuit established from the central office to the attendant's telephone and in closing the contacts 120 and 121 connects the local battery to the attendant's line through the 35 windings of coil 122. The opening of the line circuit causes the deenergization of the supervisory relay 103 which in turn opens the circuit for relay 104 and the previously described holding circuit for relay 106, but before this latter relay can release its armatures relay 118 is energized as previously described to provide another holding ground at its right hand contact for said relay 106. 40 The opening of the lower normal contact of key 116 removes ground from the conductor 123 which extends through the lower normal contact of the private branch exchange cutoff key 124 to the test terminal 45 of the row in the line finder bank with which brush 200 is associated. The closure of the lower left hand alternate contact of key 116 grounds the trunk terminal in the bank of the line finder and the closure of the lower right hand alternate contact of said key grounds the starter wire 125 extending through the normal contact of the cutoff relay 126.

As soon as the starter wire is grounded 50 a circuit is established for the line finder

test relay 201 extending from grounded battery through the winding of said relay, brush 202 of the line finder in normal position, the terminal associated therewith, the left hand normal contact of relay 203, 55 starter wire 125, the normal contact of relay 126 and the lower right hand contact of key 116 to ground. Relay 201 energizes in this circuit thereby closing a circuit for slow to release relay 204 extending from grounded battery through the winding of said relay, brush 205 of the connector, left hand normal contact of slow to release relay 206, the outer right hand normal contact of relay 207, the left hand alternate contact of relay 201, the brush 208 of the connector and the right hand normal contact of slow-to-release relay 209 to ground. The energization of relay 204 in this circuit causes the energization of relay 210 from grounded battery 60 through the winding of said relay and the left hand alternate contact of relay 204 to ground. The closure of the inner right hand alternate contact of relay 210 establishes a self-interrupting circuit for the 65 motor magnet 211 of the line finder switch extending from grounded battery through the winding and contact of said magnet of the right hand alternate contact of relay 201, the brush 200 in its normal position, 70 the inner right hand alternate contact of relay 210 and the left hand alternate contact of relay 204 to ground. The magnet 211 operates to cause the brushes of the line 75 finder switch to take one step from their normal positions. The test terminals associated with the brush 200 of the line finder switch are normally grounded either by the lower normal contact of key 116 or the normal contact of line relay 212 associated with 80 each subscriber line in the private branch exchange. Therefore, as long as the brushes of the line finder switch engages the terminals associated with idle lines a locking circuit for test relay 201 will be established 85 extending from grounded battery through the winding of said relay, brush 202, the segment 213 associated therewith, the right hand alternate contact of relay 201 and brush 200 to ground upon the test terminal. 90 Relay 201 will therefore remain operated and maintain a stepping circuit for magnet 211 extending through the winding and contact of said magnet, the right hand alternate contact of relay 201 and brush 200 to 95 ground. The magnet 211 continues to step the brushes of the line finder until a non-grounded terminal is engaged by brush 200, whereupon the locking circuit for relay 201 will be opened and this relay will release to 100 permanently break the stepping circuit. With the brushes of the switch in engagement with the terminals associated with the portion of the trunk extending from the attendant's position, a circuit is established 105 110 115 120 125 130

for line relay 214 extending from grounded battery, through the left hand winding of said relay, the outer left hand normal contact of relay 207, the middle normal contact 5 of relay 201, the brush 215, the middle normal contact of key 124, the right hand contact of listening key 114, the attendant's substation apparatus, the left hand contact of key 114, the upper normal contact of key 10 124, brush 216, the left hand normal contact of relay 201, the inner left hand normal contact of relay 207 and the right hand winding of relay 214 to ground. Relay 214 energizes and this occurs before relay 204 15 can release following the opening of its original energizing circuit through the left hand alternate contact of the test relay 201. Relay 204 will therefore be held energized over another circuit extending from 20 grounded battery through the winding of said relay, the left hand alternate contact of relay 214, the inner left hand normal contact of relay 207 and the right hand alternate contact of relay 214 to ground. Continued 25 energization of relay 204 maintains the relay 210 in its operated condition and upon engagement of the brushes of the line finder with the terminals of the trunk taken for use, a locking circuit is established for 30 relay 210 extending from grounded battery through the winding and inner right hand alternate contact of said relay, brush 217, conductor 127 and the left hand alternate contact of relay 106 to ground. The energization 35 of relay 214 also establishes a circuit for relay 203 extending from grounded battery through the winding of said relay and the right hand alternate contact of relay 214 to ground. Relay 203 energizes 40 and locks through its middle alternate contact, the inner right hand alternate contact of relay 210 and brush 217 to ground at the left hand alternate contact of relay 106. By closing its left hand alternate contact 45 relay 203 transfers the starter wire 125 to the next line finder. The closure of the right hand alternate contact of relay 203 establishes a circuit extending from ground, through the right hand alternate contact 50 of said relay, the innermost left normal contact of relay 201, the brush 218 and the winding of the cutoff relay 126 to ground. Energization of the latter relay in the circuit just described disconnects ground from 55 the starter wire 125 to prevent a second line finder from being started and also at its alternate contact again grounds the test terminal in the line finder bank associated with brush 200. The grounding of this terminal 60 however does not affect the motor magnet 211 of the line finder since the test relay 201 has already released.

The attendant may now dial for the desired connection. Let it be assumed that 65 the call is to be extended to substation 219

and that the number of this substation is 94. The attendant manipulates her impulse sending device to transmit nine impulses and upon each interruption of the line circuit, extending through the windings of relay 214, this relay releases to establish a stepping circuit for the motor magnet 220 extending from grounded battery through the winding of this magnet, the winding of relay 209, the right hand normal contact of 70 test relay 221, the right hand normal contact of relay 222, the right hand alternate contact of relay 204, which maintains its armature attracted during the transmission of the impulses, the normal contact of relay 214, the inner right hand normal contact of relay 207, the inner left hand alternate contact of relay 203 and the left hand alternate contact of relay 204 to ground. Relay 209 75 also energizes in this circuit, maintains its armatures attracted during the transmission of impulses and removes ground from brush 208. The energization of relay 209 also establishes a circuit extending from ground through the alternate contact of said relay, the normal contact of relay 223 and the winding of relay 224 to grounded battery. The energization of relay 224 opens the sleeve and test brush circuits extending 80 through brushes 225 and 226, respectively. At the termination of the nine impulses corresponding to the first digit of the called number, relay 209, after an interval releases and the test brush 226 will be engaged with 85 terminal 227 on the connector multiple bank with the other brushes on the corresponding terminals in the same vertical row. A circuit will then be established for relay 228 extending from grounded battery, through the winding of said relay, brush 208 and its 90 associated terminal and the right hand normal contact of relay 209 to ground. Relay 228 energizes and locks up in a circuit extending from grounded battery through the winding and right hand alternate contact of said relay, the inner left hand alternate contact of relay 210 and the left hand alternate contact of relay 204 to ground. Relay 224 is held energized over the brush 95 100 105 236 to ground at the left hand alternate contact of relay 210. The attendant now sends four impulses corresponding to the units digit of the called number and the stepping circuit is again closed in the same manner 110 as previously described to operate motor magnet 220 and energizes relay 209. At the termination of this series of impulses and with the brushes of the switch engaged with the terminals of the wanted line, relay 209 115 again releases. If the called substation 219 is busy due to another call from the central office, a ground will be placed upon the multiple sleeve terminal of the called line through the busy connector switch, the 120 125 brushes of which are in engagement with the 130

terminals of said line. This ground extends from the inner right hand alternate contact of relay 106 over the conductor 127, brush 217, right hand normal contact of relay 229 of the busy connector switch, the left hand normal contact of relay 224 of said switch, the next to outer right hand alternate contact of relay 210 to the brush 225 which is in engagement with the sleeve terminal of the called line. If substation 219 is busy on a local call, then the slow-to-release relay 204 of the busy connector switch remains energized throughout the call due to energization of line relay 214 and the ground potential on the sleeve terminal of the called line is extended from the left hand alternate contact of relay 204, through the inner right hand alternate contact of relay 210, the right hand normal contact of relay 229, the left hand normal contact of relay 224, the outer right hand alternate contact of relay 210 to brush 225. Thus, should substation 219 be busy when the brushes of the switch engage the terminals thereof, a circuit will be established for test relay 221 by the make-before-break contact of relay 209 before this relay is fully released to open the circuit for relay 224. This circuit for relay 221 extends from ground at the sleeve terminal of the called line through brush 225, the next to the outer right hand alternate contact of relay 210, the alternate contact of relay 224, the middle alternate contact of relay 228, the left hand normal contact and winding of relay 221, left hand normal contact of relay 209, the normal contact of relay 223 and winding of relay 224 to battery and ground, whereby relay 224 which has up to this time been held up by ground at the left-hand alternate contact of relay 209 is now held up in series with the winding of 221 by the ground on the test terminal of the called line. Relay 221 locks up through its left hand alternate contact, the innermost right hand alternate contact of relay 210 and the left hand alternate contact of relay 204 to ground. Relay 224 is held energized in this circuit. Operation of relay 221 extends ground through the right hand alternate contact of said relay, the secondary winding of the busy tone transformer 230 to one side of the trunk then in use, thence to the attendant's substation and to grounded battery through the left hand winding of line relay 214. The attendant upon hearing this busy tone, proceeds to release the connection in a manner which will later appear. The energization of relay 221 also opens at its right hand normal contact the stepping circuit for motor magnet 210 to prevent further operation thereof should additional impulses be transmitted.

If the called line is idle no ground will be found upon the sleeve terminal thereof and relay 221 will fail to operate. Relay

224 will therefore release as soon as the alternate contact of relay 209 is opened. The release of relay 224 establishes a circuit extending from ground through the left hand alternate contact of relay 204, the inner right hand alternate contact of relay 210, the right hand normal contact of relay 229, the left hand normal contact of relay 224, the next to outer right hand alternate contact of relay 210, brush 225 and the winding of the cutoff relay of the called line similar to cutoff relay 231 shown at the left of Fig. 2 to grounded battery. The cutoff relay of the called line thereupon operates and prevents energization of the line relay 204 individual to said called line should the subscriber remove his receiver from the switch hook to initiate another call. Relay 222 is now energized over a circuit extending from grounded battery through the winding of said relay, the right hand normal contact of relay 206, the normal contact of relay 232, the left hand alternate contact of relay 228, the right hand normal contact of relay 224, the next to the innermost right hand alternate contact of relay 210, and test brush 226 to ground. Relay 222 energizes and connects ringing current to the called line over a circuit extending from grounded battery through the secondary winding of the ringing transformer 233, left hand winding of relay 206, the left hand alternate contact of relay 222, brush 234, the ringing apparatus at the called substation, brush 205 and the inner left hand alternate contact of relay 222 to ground. Relay 206 is not energized in this circuit until the called subscriber removes his receiver from his switch hook whereupon sufficient current flows through the left hand winding of relay 206 to cause it to attract its armatures. In operating, relay 206 opens the energizing circuit for relay 222 which thereupon disconnects the ringing current from the called line. Relay 206 locks up over a circuit extending through its right hand winding and inner right hand alternate contact and from thence over the previously described energizing circuit for relay 222 to ground at the test brush 226. The energization of relay 206 also establishes a circuit extending from ground through the outer right hand alternate contact of relay 206 and winding of relay 223 to grounded battery. Relay 223 energizes and establishes a circuit for relay 232 extending from grounded battery through the left hand winding of relay 232, the alternate contact of relay 223, brush 235 of the line finder and the lowermost left hand alternate contact of central office cutoff key 116 to ground. Relay 232 energizes and locks up over a circuit extending from grounded battery through the right hand winding and right hand alternate contact of said relay, the left hand alternate contact of relay 228,

the right hand normal contact of relay 224, next to the innermost right hand alternate contact of relay 210 and test brush 226 to ground. The energization of relay 232 opens the locking circuit for relay 206 which extends through the normal contact of said relay 232 and relay 206, after an interval, releases. In so doing, the energizing circuit for relay 223 is also opened and this relay releases. Energization of relay 232 also establishes a circuit for relay 207 extending from grounded battery through the winding of this relay and the left hand alternate contact of relay 232 to ground. Relay 207, upon energizing, connects the trunk through from the attendant's position to the called substation, and causes the release of line relay 214 and relay 204.

The operation of the connector switch would be the same as just described if the wanted line had been in the group of lines having 4 as the first digit instead of 9. In establishing calls wherein the wanted line has three digits, the operation will again be the same, the first digit 9 carrying the switch to the row of terminals including the terminal 227, the section digit 9 carrying the switch to the row of terminals similar to the first mentioned row but not shown on the connector bank in Fig. 2, while the third digit operates the switch to engage terminals of the wanted line.

The called subscriber at substation 219 having answered, the attendant then restores listening key 114 and central office cutoff key 116 to their normal positions and the latter key, when restored, extends the trunk from the central office through to the called subscriber's substation, whereupon the calling and called subscribers may converse. The supervisory relay 103 is energized in the conversational circuit and maintains energized relays 104, 106, 110, 112 and 107.

At the termination of the conversation, the replacing of the receiver upon its switch hook at the called substation causes the release of the supervisory relay 103, which, upon deenergizing, opens the circuit for relay 104, whereupon relay 105 becomes energized and holds relays 106, 110, 112 and 107 energized. When the called subscriber hangs up and thereby releases relay 103, the supervisory lamp at the central office is again lighted to indicate to the operator thereat that the call has been terminated and she then removes the plug from jack 100. This releases relay 105 which opens the holding circuit for relay 106 and the latter relay, upon deenergizing, removes the holding ground from conductor 127 to cause the release of the switches employed in establishing the connection.

The removal of ground from the left hand alternate contact of relay 106 opens the previously described locking circuit for re-

lays 203 and 210 which thereupon release. Restoration of relay 203 opens the holding circuit for relay 126 through brush 218 and relay 126 then releases. Upon the release of relay 210, a stepping circuit for the line finder is closed extending from grounded battery through the winding and contact of motor magnet 211, brush 237 and the left hand normal contact of relay 210, to ground. This circuit, being self-interrupting, causes the motor magnet to step the line finder switch back to its normal position. The release of relay 210 also opens the locking circuit for relay 228 which extended through the innermost right hand alternate contact of relay 210, and relay 228 in releasing, opens the locking circuit for relay 232 which extended through the left hand alternate contact of relay 228. Ground being removed from the left hand alternate contact of relay 232, the holding circuit for relay 207 is opened and this relay releases with the brushes of the connector still in engagement with the terminals of the called line. A circuit is now established for relay 229 extending from grounded battery, through the winding of this relay, a right hand normal contact of relay 210 and brush 226 to ground. Relay 229 energizes and in so doing establishes a self-interrupting circuit for the motor magnet 220 of the connector switch, said circuit extending from grounded battery through the winding of said magnet, the winding of relay 209, the contact of magnet 220, a right hand alternate contact of relay 229 and the right hand normal contact of relay 203 to ground. Magnet 220 therefore operates to step the brushes of the connector switch towards their normal position and as long as the brush 226 is passing over test terminals connected to ground, this self-interrupting circuit will be maintained. When brush 226 engages the last terminal in the connector bank, the ground for the continued maintenance for relay 229 is found at the normal contact with relay 204 which was previously released by the energization of relay 207 at the time that the connection was established. The motor magnet 220 is therefore again operated to step the switch from the last set of terminals to normal whereupon relay 229, no longer finding ground, releases. A more detailed description of the release of the connector switch will appear later.

Should the attendant desire to answer another call before the one to the subscriber is completed, she may restore key 116 and hold the central office trunk to prevent the operation of the disconnect signal thereat by operating key 128 which, at its left contact, closes a circuit to energize relay 118. Ground is then maintained through the winding of relay 106 to prevent the release thereof. The right hand contact of

key 128 prepares a circuit for lamp 129 through the left hand normal contact of relay 104, but this relay is energized due to the operation of relay 103. If, at the termination of the conversation which results in the release of relays 103 and 104, the holding key 128 is still operated, the attendant will be informed of this by the lighting of lamp 129.

¹⁰ *Establishment of a call between subscribers within the exchange.*

Let it now be assumed that a subscriber within the private branch exchange at substation 238 desires to establish a connection to the subscriber at substation 219. The removal of the receiver from its switch hook at substation 238 establishes an obvious circuit from relay 212 individual to said substation. This relay, in closing its alternate contact, closes a circuit extending from ground through contact of relay 212, the left hand normal contact of relay 203, brush 202 and the winding of test relay 201 to grounded battery. Relay 201 energizes to establish an energizing circuit for relay 204 through brush 205 of the connector switch to ground at relay 209 as previously described. The connection of ground to the left hand alternate contact of relay 204 energizes relay 210 over an obvious circuit, whereupon motor magnet 211 will be operated in the same manner as described in connection with the establishment of a call from central office to step the brushes of the line finder from their normal position. The idle condition of the subscribers' lines being denoted by ground upon the terminals over which brush 200 passes, it will be obvious that as long as said brush is passing over terminals having ground connected thereto, the circuit for test relay 201 will be maintained and motor magnet 211 will continue to step the brushes of the switch. When the brush 200 engages the terminal individual to substation 238 which is free from ground, relay 201 releases and the stepping circuit of the line finder is permanently opened, whereupon the brushes of the switch are brought to rest upon the terminals individual to the calling line. The release of relay 201 opens the circuit for relay 204 and immediately establishes a circuit for line relay 214 extending from grounded battery, through the left hand winding of said relay, the outer left hand normal contact of relay 207, the middle normal contact of relay 201, brush 215, the apparatus at substation 238, the brush 216, left hand normal contact of relay 201, the inner left hand normal contact of relay 207 and the right hand winding of relay 214 to ground. This circuit is closed and relay 214 energizes before relay 204 can release so that this latter relay will now be maintained energized through the alternate con-

tacts of relay 214. Relay 204 therefore maintains a holding circuit for relay 210. The energization of relay 214 also establishes the previously described energizing circuit for relay 203 which, upon energizing, locks ⁷⁰ up to ground at the left hand alternate contact of relay 204. The energization of relay 203 transfers the starter wire to the next line finder and establishes a circuit for cutoff relay 231 individual to the calling line, said circuit extending from grounded battery through the winding of relay 231, brush 218, the inner left hand normal contact of relay 201 and the right hand alternate contact of relay 203 to ground. Relay 231 energizes and opens the energizing circuit for line relay 212 which thereupon releases to again connect ground to the test terminal individual to the calling line.

The subscriber at the calling substation may now proceed to dial the wanted number and in response to the impulses the connector switch operates in the same manner as described in connection with a call from central office until the point is reached in the ⁹⁰ operation where relay 223 energizes due to the operation of relay 206. It will be recalled that at this time relay 223, in closing its alternate contact, established an energizing circuit for relay 232 which extended ⁹⁵ through the brush 235 to the lower left hand alternate contact of key 116. It will be noted that in the operation of connecting two subscribers, the terminals of subscribers' lines engaged by brush 235 of the line ¹⁰⁰ finder have no connections thereto. Thus, with the brush 235 resting upon the terminal individual to the calling line, no circuit will be established for relay 232 and this relay will remain in its normal condition. It will ¹⁰⁵ also be recalled that, upon the energization of relay 206, a locking circuit was established for this relay extending through its right hand winding and inner right hand alternate contact, the normal contact of relay 232, the left hand alternate contact of relay 228, the right hand normal contact of relay 224, the next to the innermost right hand alternate contact of relay 210 and the brush ¹¹⁰ 226 to ground. Inasmuch as relay 232 is ¹¹⁵ not energized, this locking circuit for relay 206 will be maintained throughout the duration of the call between the subscribers, and relay 207 will fail to operate. The talking circuit will therefore extend through the left hand normal contacts of relay 207 and the left hand alternate contacts of relay 206. Battery for talking purposes is supplied to the called subscriber's substation over a circuit extending from battery ¹²⁵ through the right hand winding of impedance coil 239, the inner left hand alternate contact of relay 206, the left hand normal contact of relay 222, brush 234, called subscriber's substation apparatus, brush 205, the ¹³⁰

outer left hand alternate contact of relay 206, the left hand winding of relay 239, the inner right hand alternate contact of relay 206 and from thence over the locking circuit of this relay to ground at the brush 226. On termination of the conversation between the subscribers, the release of the line finder and connector switches employed is the same as previously described with the exception that the release of relay 210 accomplishes the deenergization of relay 206 instead of relay 232 and the release of the former relay opens the circuit of the coil 239.

15 *Outgoing call to central office.*

A subscriber within the private branch exchange may initiate calls direct to the central office and may employ any one of the trunks extending between the central office 20 and the private branch exchange by operating a connector switch to cause the same to trunk hunt. Should the subscriber at substation 238 desire a central office connection, the removal of the receiver from its switch hook at the substation will cause the line finder to operate in the same manner as previously described, whereupon the subscriber actuates his impulse sending device to transmit one impulse. The brushes of the connector switch are thereby caused to take one 25 step from their normal positions and engage the second row of terminals in the connector bank. After an interval following the termination of the impulse, relay 209 releases and establishes a circuit for the trunk test 30 relay 229 extending from ground on the right hand normal contact of relay 209, brush 208 and the winding of relay 229 to grounded battery. Relay 229 energizes and, 35 in so doing, causes the operation of relay 240 over a circuit traceable from grounded battery through the winding of relay 240, brush 226, the next to the innermost right hand alternate contact of relay 210, the 40 right hand normal contact of relay 224, the normal contact of relay 228, the left hand alternate contact of relay 229, brush 208 and the right hand alternate contact of relay 209 to ground. Relay 240 energizes to 45 remove ground from its normal contact which is connected to all of the test terminals of the central office trunks. Relay 240 locks over a circuit extending from grounded battery through the winding and left 50 hand alternate contact of said relay, the right hand alternate contact of relay 229 and the right hand alternate contact of relay 240 to ground. The energization of relay 240 also establishes a stepping circuit for 55 motor magnet 220 at the connector switch extending from grounded battery through the winding of said magnet, the winding of relay 209, the contact of magnet 220, the left hand alternate contact of relay 240 and from thence over the energizing circuit of

relay 240 to ground at the right hand normal contact of relay 209. The first energization of magnet 220 over this circuit steps the brushes of the switch from the second row of terminals in the bank onto the 70 terminals of the first central office trunk. The busy condition of trunks to the central office is denoted by ground upon the test conductor of the trunks extending from the right hand alternate contact of relay 106 or the similar contact of relay 112. If the first trunk leading to central office is busy, ground will therefore be extended through the sleeve brush 225, the middle right hand alternate contact of relay 210, the left hand 75 normal contact of relay 224, the middle alternate contact of relay 229 and the winding of this relay to grounded battery. Relay 229 will therefore remain energized and maintain a stepping circuit for motor magnet 220 extending from the right hand alternate contact of relay 106 or the similar contact of relay 112. If the first trunk leading to central office is busy, ground will therefore be extended through the sleeve brush 80 225, the middle right hand alternate contact of relay 210, the left hand normal contact of relay 224, the middle alternate contact of relay 229 and the winding of this relay to grounded battery. Relay 229 will therefore remain energized and maintain a stepping circuit for motor magnet 220 extending from grounded battery through the winding of this magnet the winding of relay 209, the 85 contact of magnet 220, the right hand alternate contact of relay 229 and the right hand alternate contact of relay 240 to ground. Motor magnet 220 will therefore continue to operate and step the brushes of the connector switch until brush 225 encounters a terminal free from ground. The locking circuit for relay 229 will then be opened and this relay will release to permanently open the stepping circuit, whereupon the brushes 90 of the switch will be brought to rest upon the terminals of the idle trunk leading to central office. The release of relay 229 also opens the locking circuit for relay 240 which thereupon restores to again place ground upon the terminals of the central office trunk 95 100 engaged by brush 226. The circuit is now established for relay 207 extending from grounded battery through the winding of said relay, the left hand normal contact of relay 229, the normal contact of relay 228, the right hand normal contact of relay 224, the next to the innermost right hand alternate contact of relay 210, the brush 226 and the normal contact of relay 240 to ground. Energization of relay 207 connects the talk- 105 110 115 120 125 130 135 140 145 150 155 160 165 170 175 180 185 190 195 198 200 205 210 215 220 225 230 235 240 245 250 255 260 265 270 275 280 285 290 relay, the middle normal contact of relay 110, the lower talking conductor, brush 234 of the connector switch, the left hand normal contact of relay 222, the outer left hand alternate contact of relay 207, the middle normal contact of relay 201, brush 215 of the line finder, the calling subscriber's substation apparatus, brush 216, the left hand normal contact of relay 201, the right hand alternate contact of relay 207, brush 205, the upper conductor of the trunk, the right hand normal contact of relay 110 and the right hand winding of relay 115 to ground. Relay 115 energizes and establishes an obvious circuit for relay 112 which, in energizing, causes the operation of relay 107 to light the busy lamp 108. The energization of relay 112 also grounds the test conductor of the trunk terminating in the multiple bank of the connector switch so that this trunk will test busy on other calls. The energization of line relay 115 extends the ground from the normal contact of relay 106 through the left hand alternate contact of relay 115 to the tip side of the trunk terminating at the central office, whereupon the line relay 102 at said office is energized to light the lamp 130 associated with the trunk taken for use to indicate to the central office operator that a call is awaiting attention. The operator then inserts the plug into jack 100, whereupon the trunk relays shown in Fig. 1 will operate in the same manner as described in connection with a call from central office. Upon the energization of relay 106 a circuit is established for relay 110 through the left hand alternate contact of relay 112 to ground at the left hand alternate contact of relay 106. Relay 110 energizes to open energizing circuit for relay 115 and extends the calling line through to the central office operator's cord circuit.

At the termination of the call, the replacing of the receiver upon the switch hook at the called substation caused the release of the supervisory relay in the central office operator's cord circuit which results in the lighting of the supervisory lamp thereof in the usual well-known manner. The central office operator then removes the plug from jack 100 to restore to normal the apparatus associated with the trunk in Fig. 1 in the same manner as previously described. The restoration of the receiver upon the switch hook at the called substation also opens the circuit of supervisory relay 103 which thereupon deenergizes to release relay 106. Upon deenergization of the latter relay the holding ground at its right hand alternate contact is removed from relay 210 and this relay thereupon releases. The self-interrupting circuit for motor magnet 211 of the line finder switch is now closed as previously described to step the brushes of the switch to their normal position. The release of relay

210 also establishes a circuit for relay 229 extending from grounded battery through the winding of said relay, the middle normal contact of relay 210, test brush 226, engaged test terminal and the normal contact of relay 240 to ground. Relay 229 energizes to close a stepping circuit for motor magnet 220 extending from grounded battery through the winding of said magnet, winding of relay 209, the contact of magnet 220, the right-hand alternate contact of relay 229 and the right-hand normal contact of relay 203 which was deenergized upon the release of relay 204. Magnet 220 operates in this circuit to step the brushes of the connector switch from the terminals engaged to the next set of terminals in the connector bank. It will be obvious, that as long as the brush 226 encounters ground upon its associated terminals, the circuit for relay 229 will be maintained to cause the continued operation of the motor magnet. In the case of all subscribers' lines, ground is connected directly to the terminals over which brush 226 passes. When said brush engages terminal 227, ground will be found at the normal contact of relay 204. Ground is placed upon the next succeeding terminal from the right-hand normal contact of relay 210 and when brush 226 engages the terminals individual to the trunks extending to the attendant's position, ground is found at the normal contact of relay 241. The last test terminal in the connector bank is connected to ground at the normal contact of relay 204 and it will thus be obvious that magnet 220 will operate to step the brushes and the switch to their normal positions. Relay 229, no longer finding ground, will release to permanently open the stepping circuit for the switch which will thereupon be in a position to extend another call.

Subscriber initiates a call to the attendant.

A subscriber within the private branch exchange may establish a connection to the attendant's position by dialing the digit 0 after removing receiver from its switch hook at the calling substation. In response to the ten impulses transmitted, the connector switch operates as previously described, to engage the brushes with the eighth set of terminals shown in the connected bank. Relay 209 then releases as before, to establish a circuit for relay 229 through brush 208. The energization of relay 229 in this circuit establishes an energizing circuit for relay 241 traceable from grounded battery through the winding of said relay, the outermost right-hand alternate contact of relay 210, test brush 226 next to the innermost right-hand alternate contact of relay 210, the right-hand normal contact of relay 224, the normal contact of relay 228, the left-hand alternate contact of relay 229 and from

thence over the energizing circuit for the latter relay to ground at the right-hand normal contact of relay 209. Relay 241 locks in a circuit extending through its winding and 5 left-hand alternate contact, the right-hand alternate contact of relay 229 and the right-hand alternate contact of relay 241 to ground. A stepping circuit is now established for 10 motor magnet 220 extending from grounded battery through the winding of said magnet, the winding of relay 209, the contact of magnet 220, the right-hand alternate contact of relay 229, and the right-hand alternate contact of relay 241 to ground. Magnet 15 net 220 operates to step the brushes of the switch over terminals associated with trunks leading to the attendant's position. The busy condition of these trunks is denoted by ground upon the sleeve terminals thereof, 20 over which brush 225 passes, said ground being extended to each sleeve terminal from the left-hand alternate contact of relay 204 of the busy switch connected to the trunk extending to the operator's position, through 25 the innermost right-hand alternate contact of relay 210 of said switch, the right-hand normal contact of relay 229, the left-hand normal contact of relay 224, next to the outermost right-hand alternate contact of relay 210 to the brush 225. Therefore, should the brush 225 of the connector switch now seeking an 30 idle trunk leading to the attendant's position encounter ground upon the sleeve terminal of the first trunk, a locking circuit will be maintained for relay 229 extending through the winding and the middle alternate contact of said relay, the left-hand normal contact of relay 224 and from thence 35 over the path just traced to the brush 225. Relay 229 therefore, remains energized to cause the continued operation of magnet 220. When brush 225 encounters a terminal free from ground, relay 229 releases to per- 40 manently open the stepping circuit of the connector switch whereupon the brushes thereof come to rest upon the set of terminals individual to the selected idle trunk extending to the attendant's position. The 45 release of relay 229 also opens the locking circuit for relay 241 which thereupon deenergizes to again place ground upon the test terminals individual to the trunks extending to the attendant's position. Each trunk ter- 50 minating at the attendant's position has asso- 55 ciated therewith, a lamp 181 which is lighted when the trunk is seized, over a circuit traceable from grounded battery through said lamp, the normal contact of the key 132, 60 the sleeve terminal of the trunk in the connector bank, the brush 225, the next to the outermost right-hand alternate contact of relay 210, the normal contact of relay 224, the right-hand normal contact of relay 229, 65 the innermost right-hand alternate contact of

relay 210 and the left-hand alternate contact of relay 204 to ground. The attendant observing the lighted condition of the lamp 181, can now operate the key 132 of the trunk taken for use and thereby connect 70 her telephone set with the calling substation line. At the termination of the conversation between the subscriber and the attendant, the replacing of the receiver upon the switch hook at the calling substation again 75 causes the release of the line finder and the connector switches in the same manner as previously described.

The attendant may initiate a call direct to central office by operating the listening 80 key 114 whereupon line relay 115 is energized with the result that the central office operator is signaled as previously described in connection with the establishment of a call from a subscriber to central office. 85

What is claimed is:

1. In a telephone system, a branch office, a main office, connecting circuits including numerical automatic switching mechanism at the branch office, an attendant's position 90 thereat, subscribers' lines terminating at the branch office, senders associated therewith for setting said switching mechanism to interconnect said lines, a trunk extending between said offices, a signal for said trunk at 95 the branch office actuated when the trunk is taken for use at the main office, means controlled from said position for causing said trunk to be connected to an idle one of said connecting circuits, and a sender for setting 100 the numerical automatic switching mechanism thereof to select the desired subscriber's line.

2. In a telephone system, a branch office, a main office, connecting circuits including numerical automatic switching mechanism at the branch office, an attendant's position 105 thereat, subscribers' lines terminating at the branch office, senders associated therewith for setting said switching mechanism to interconnect said lines, a trunk extending between said offices, a signal for said trunk at the branch office actuated when the trunk is taken for use at the main office, an automatic non-numerical switch, means controlled by 110 the attendant for causing said non-numerical switch to connect said trunk to said numerical switching mechanism, and a sender for setting said mechanism to connect with a subscriber's line. 115

3. In a telephone system, a branch office, a main office, connecting circuits including numerical automatic switching mechanism at the branch office, an attendant's position 120 thereat, subscribers' lines terminating at the branch office, senders associated therewith for setting said switching mechanism to interconnect said lines, a trunk extending between said offices, a signal for said trunk at 125 the branch office actuated when the trunk is 130

taken for use at the main office, an automatic non-numerical switch, means controlled by the attendant for causing said non-numerical switch to connect said trunk to said numerical switching mechanism, and a sender at said position for setting said mechanism to connect with a subscriber's line.

4. In a telephone system, a private branch exchange, subscribers' lines terminating thereat, connecting circuits thereat including numerical automatic switching mechanism, senders associated with said subscribers' lines for setting said switching mechanism to interconnect a pair of said lines, a central office, trunks extending therefrom to the private branch exchange, means controlled by the attendant thereat for causing a calling incoming trunk to be connected to an idle one of said connecting circuits, and a sender for controlling the numerical automatic switching mechanism of said connecting circuit to connect the calling trunk with the desired subscriber's line.

5. In a telephone system, a private branch exchange, subscribers' lines terminating thereat, connecting circuits thereat including numerical automatic switching mechanism, senders associated with said subscribers' lines for setting said switching mechanism to interconnect a pair of said lines, a central office, trunks extending therefrom to the private branch exchange, means controlled by the attendant thereat for causing a calling incoming trunk to be connected to an idle one of said connecting circuits, a sender, means for connecting the same to the calling trunk to control the numerical automatic switching mechanism of said connecting circuit to connect the calling trunk with the desired subscriber's line.

6. In a telephone system, subscribers' lines, a private branch exchange wherein said lines terminate, connecting circuits at said private branch exchange, each including a finder switch, numerical automatic switching mechanism, senders for said subscribers' lines for building up connections between subscribers' lines by means of said switches, a central office, trunks extending therefrom to said private branch exchange, an attendant station at said private branch exchange, signals thereat for said trunks, means controlled by the attendant for causing an idle finder to connect with a calling trunk, and a sender for setting the associated numerical automatic switching mechanism to connect the calling trunk with the desired subscriber's line.

7. In a telephone system, subscribers' lines, a private branch exchange wherein said lines terminate, connecting circuits at said private branch exchange, each including a finder switch and numerical automatic switching mechanism, senders for said subscribers' lines for building up con-

nections between subscribers' lines by means of said switches, a central office, trunks extending therefrom to said private branch exchange, an attendant's station at said private branch exchange, signals thereat for said trunks, means controlled by the attendant for causing an idle finder to connect with a calling trunk, and a sender at said position for setting the numerical automatic switching mechanism to connect the calling trunk with the desired subscriber's line.

8. In a telephone system, subscribers' lines, a private branch exchange wherein said lines terminate, connecting circuits at said private branch exchange, each including a finder switch and a connector switch, senders for said subscribers' lines for building up local connections by means of said switches, a central office, trunks extending therefrom to said private branch exchange and terminating thereat in fixed terminals at said finders, an attendant's station at said private branch exchange, signals thereat for said trunks, means controlled by the attendant for causing an idle finder to select a calling trunk, and a sender for setting the associated connector to connect the calling trunk with the desired subscriber's line.

9. In a telephone system, subscribers' lines, a private branch exchange wherein said lines terminate, connecting circuits at said private branch exchange, each including a finder switch and a connector switch, senders for said subscribers' lines for building up local connections by means of said switches, a central office, trunks extending therefrom to said private branch exchange and terminating thereat in fixed terminals at said finders, an attendant's station at said private branch exchange, signals thereat for said trunks, means controlled by the attendant for causing an idle finder to select a calling trunk, and a sender at said position for setting the associated connector to connect the calling trunk with the desired subscriber's line.

10. In a telephone system, subscribers' lines, a private branch exchange wherein said lines terminate, connecting circuits at said private branch exchange, each including a finder switch and numerical automatic switching mechanism, senders for said subscribers' lines for building up local connections by means of said connecting circuits, a central office, trunks extending therefrom to said private branch exchange and terminating thereat in fixed terminals at said finder switches, an attendant's station at said private branch exchange, signals thereat for said trunks, means controlled by the attendant for causing an idle finder to select a calling trunk, a sender for setting the associated numerical automatic switch-

ing mechanism to connect the calling trunk with the desired subscriber's line, and other trunks extending from said private branch exchange to said central office and terminating in fixed terminals at said numerical automatic switching mechanism for extending connections from said subscribers' lines to said central office.

11. In a telephone system, subscribers' lines, a private branch exchange wherein said lines terminate, connecting circuits at said private branch exchange each including a finder switch and numerical automatic switching mechanism, senders for said subscribers' lines for building up local connections by means of said connecting circuits, a central office, trunks extending therefrom to said private branch exchange and terminating thereat in fixed terminals at said finder switches, an attendant's station at said private branch exchange, signals thereat for said trunks, means controlled by the attendant for causing an idle finder to select a calling trunk, a sender for setting the associated numerical automatic switching mechanism to connect the calling trunk with the desired subscriber's line, and other trunks terminating in fixed terminals at said numerical automatic switching mechanism and leading to said attendant's station for extending connections from said subscribers' lines to said station.

12. In a telephone system, subscribers' lines, a private branch exchange wherein said lines terminate, an attendant's station thereat, connecting circuits at said private branch exchange each including a finder switch and a connector, senders for said subscribers' lines for building up local connections by means of said connecting circuits, a central office, trunks extending therefrom to said private branch exchange and terminating thereat in fixed terminals at said private branch exchange, signals thereat for said trunks, means controlled by the attendant for causing an idle finder to select a calling trunk, means for setting the associated connector to connect the calling trunk with the desired subscriber's line, trunks terminating in fixed terminals in said connector, and extending to the central office, and other trunks terminating in fixed terminals in said connector and extending to said attendant's station, said connector being arranged to select an idle trunk in either group under control of said sender.

13. In a telephone system, subscribers' lines, a private branch exchange wherein said lines terminate, an attendant's station thereat, connecting circuits at said private branch exchange each including a finder switch and a connector, senders for said subscribers' lines for building up local connections by means of said connecting circuits, a central office, trunks extending

therefrom to said private branch exchange and terminating thereat in fixed terminals at said private branch exchange, signals thereat for said trunks, means controlled by the attendant for causing an idle finder to select a calling trunk, means for setting the associated connector to connect the calling trunk with the desired subscriber's line, and trunks terminating in fixed terminals in said connector and extending to said attendant's station and to said central office, said trunks being arranged in a single row in said connector, said connectors being adapted under control of said senders to select a trunk of either character.

14. In a telephone system, subscribers' lines, a private branch exchange wherein said lines terminate, an attendant's station thereat, connecting circuits at said private branch exchange each including a finder switch and a single movement connector, wherein said lines terminate, senders for said subscribers' lines for building up local connections by means of said connecting circuits, a central office, trunks extending therefrom to said private branch exchange and terminating thereat in fixed terminals at said private branch exchange, signals thereat for said trunks, means controlled by the attendant for causing an idle finder to select a calling trunk, means for setting the associated connector to connect the calling trunk with the desired subscriber's line, and trunks terminating in fixed terminals in said connector, one group of said trunks leading to said attendant's station and another group of said trunks leading to the central office, said trunks being arranged in groups in a single row in said connector, whereby the connector may be set by a number of sets of impulses from a subscriber's sender to pick out a local subscriber's line or a trunk in either group.

15. In a telephone exchange system, a private branch exchange wherein said lines terminate, an attendant's position thereat, connecting circuits including finders and connectors, subscribers' lines terminating in said finders and connectors, a central office, trunks leading from said central office and terminating in said finders, a signal and a manual switch for each trunk at said private branch exchange, means controlled by said manual switch for causing an idle finder to extend a calling trunk to the associated connector, and a sender at said position for connecting the said trunk with the desired subscriber's line.

16. In a telephone system, a private branch exchange, subscribers' lines terminating thereat, connecting circuits thereat including numerical automatic switching mechanism, senders associated with said subscribers' lines for setting said switching mechanism to interconnect a pair of said

lines, a central office, trunks extending therefrom to the private branch exchange, means for causing a calling incoming trunk to be connected to an idle one of said connecting circuits, and a sender for controlling the numerical automatic switching mechanism of said connecting circuit to connect the calling trunk with the desired subscriber's line.

17. In a telephone system, a private branch exchange, subscribers' lines terminat-

ing thereat, connecting circuits thereat for extending connections, a central office, trunks extending therefrom to the private branch exchange, and line finders for said connecting circuits for extending connections from said connecting circuits to said subscribers' lines or to said trunk lines.

In witness whereof, I hereunto subscribe my name this 15th day of July A. D., 1920.

LEO KELLER.
